[57] ABSTRACT

Propulsion and steering apparatus for a marine vessel providing for 360° rotation of the propulsion unit about its vertical axis. The propulsion drive shaft is coupled to a parallel, double pinion gear by a chain drive, the double pinion and propulsion shaft being in fixed relation with respect to each other. The double pinion gear is engaged by a receiving circular rack gear rotatable about the vertical axis of the chain drive, the receiving rack gear being driven by a power source. The propulsion shaft, chain drive and double gear shaft are disposed within a vertical housing, the total vertical housing being rotatable through 360° of arc.

1 MARINE PROPULSION AND STEERING APPARATUS

This is a continuation-in-part of my application Ser. No. 30,763 filed Apr. 22, 1970 abandoned.

BACKGROUND OF THE INVENTION

1. Field of the Invention

The present invention marine propulsion and steering apparatus is generally related to marine propulsion systems and, more particularly, to combined steering-propulsion systems.

2. Prior Art

The proliferation in the number of commercial and private marine vessels has made it increasingly evident that improved propulsion and steering apparatus are needed. The prior art discloses many different categories of mechanisms for a propelling and steering a marine vessel. One of the most common devices disclosed by the prior art incorporates a propeller shaft disposed through the hull of the vessel, the shaft being rotated by an inboard power source. Other devices disclosed by the prior art comprises a variety of inboard-outboard drives. A typical inboard-outboard drive utilizes a pair of horizontal, vertically spaced shafts linked by a pulley-belt assembly or other torque transmitting means, one shaft being coupled to a propeller, the second shaft being directly coupled to a power source. One problem which is inherent in this device is the limitation in the allowable deflection of the coupling between the driving shaft and the power source. This problem is acute when referring to the need to provide both forward and reverse motive force to the vessel. This problem has been overcome in the prior art only by providing means for reversing the torque transmitted by the power source. Where the allowable deflection of the coupling is not sufficient to permit a full 360° rotation, external rudders are generally used to provide sufficient maneuverability to the vessel.

Other propulsion devices disclosed by the prior art transmit the torque of the power source to a combination of bevel gears, one gear being attached to the propeller shaft, the second mating bevel gear typically being secured to a vertically disposed rotating shaft coupling the power source and the propeller shaft. One of the problems inherent in this design is the failure of the bevel gear assembly due to water contamination. Since this portion of the device disclosed by the prior art is typically submerged in water at all times, any leak or other water contamination will cause deterioration and eventual failure of the gear units.

The present invention marine propulsion and steering apparatus solves the problems left unresolved by the prior art by utilizing a chain drive system which permits 360° rotation of the entire power drive. By permitting the power unit to rotate a full 360° of arc, the present invention eliminates the need for reversing gears or other means for reversing the torque of the power source. In addition, the use of chain drive precludes the failure problems inherent in those devices disclosed by the prior art.

SUMMARY OF THE INVENTION

The present invention marine propulsion and steering apparatus utilizes a propeller shaft rotatable by one or more chain drive couplings. The propeller shaft is disposed horizontally, a double pinion or bevel gear

shaft being disposed parallel to the propeller shaft, the double pinion gear shaft being rotated in vertical, spaced relation above the propeller shaft. The propeller shaft and pinion gear shaft are journeled within the housing of the propulsion apparatus and define a plane surface between the two shafts. A circular rack gear having inner and outer gear surfaces is freely rotatable about the housing of the chain drive, the inner rack gear mating with the pinion gears of the double pinion gear shaft. The power source is coupled to the outer rack gear by a pinion gear which will transmit the torque of the power source to the pinion gear shaft through rotation of the circular rack gear. The housing for the chain drive and the propeller shaft is rotated to control the direction in which the vessel will be moved. Since the rack gear is fully rotatable with respect to the housing of the chain drive and propeller shaft, the full torque of the power source will be transmitted to the double pinion gear shaft irrespective of the position of the pinion gear shaft and the propeller shaft in relation to the hull of the vessel.

It is therefore an object of the present invention to provide an improved propulsion and steering apparatus.

It is another object of the present invention to provide a propulsion and steering apparatus rotatable through a full 360° of arc.

It is still yet another object of the present invention to provide a marine propulsion and steering apparatus which isolates the driving members to the propeller shaft from the remaining driving members to preclude water contamination.

It is yet another object of the present invention to provide a marine propulsion and steering apparatus capable of supplying full power through a full 360° of arc.

It is still yet another object of the present invention to provide a marine propulsion and steering apparatus which is substantially simplified and economical to fabricate.

The novel features which are believed to be characteristic of the invention, both as to its organization and method of operation, together with further objectives and advantages thereof, will be better understood from the following description considered in connection with the accompanying drawing in which a presently preferred embodiment of the invention is illustrated by way of example. It is to be expressly understood, however, that the drawing is for the purpose of illustration and description only and is not intended as a definition of the limits of the invention.

BRIEF DESCRIPTION OF THE DRAWING

FIG. 1 is a side elevation, cross-sectional view of a marine propulsion and steering apparatus in accordance with the present invention.

FIG. 2 is a top plan view, in a partial cross-section, of a marine propulsion steering apparatus in accordance with the present invention taken through line 2—2 of FIG. 1.

FIG. 3 is a schematic, perspective view of the cooperating elements of the present invention illustrating the steering and propulsion members thereof.

DESCRIPTION OF THE PRESENTLY PREFERRED EMBODIMENT

An understanding of the structure of the present invention can be best gained by reference to FIG. 1

wherein a side elevation, cross-sectional view of a propulsion and steering apparatus in accordance with the present invention is shown. Power source drive shaft 1 is rotatably mounted through a side wall of gear housing 2. Power source drive shaft 1 is connected to a conventional power source used for marine propulsion mechanisms, the power source typically being an internal combustion engine, gas turbine or other similar energy source. Power source drive shaft 1 transmits the output torque of the power source, the power source being conventional and not shown. Pinion gear 3 depends from power source drive shaft 1 and converts the direction of the rotation force by 90° of arc. Pinion gear 3 is coupled to receiving outer rack gear 4. Outer rack gear 4 and inner rack gear 5 are circular gears integral with each other and rotatably journeled upon suitable bearings 6 about chain assembly housing 7. Integral rack gears 4 and 5 are journeled upon bearings 6 with respect to the hull of the marine vessel upon which the present invention is mounted.

Chain assembly housing 7 is a substantially cylindrical member coupled to the vessel hull and journeled about the vertical axis of housing 7 in suitable bearings 8 and 9. Double pinion gear shaft 10 is disposed through and mounted perpendicular to the vertical axis of chain assembly housing 7, double pinion gear shaft 10 being rotatably mounted along its horizontal axis in suitable bearings. Double pinion gear shaft 10 is rotatable about its horizontal axis while being stationary with respect to the vertical axis of chain assembly housing 7. Depending from the axial ends of double pinion shaft 10 are pinion or bevel gears 11 and 12. Pinion gears 11 and 12 are meshed with inner rack gear 5 at diametrically opposed locations along the circumference of rack gear 5. Double pinion gears 11 and 12 stabilize and balance pinion gear shaft 10 and thereby relieve the mechanical stress imposed on the bearings within which shaft 10 is journeled.

Sprockets 13 are disposed about and secured to double pinion gear shaft 10 within chain assembly housing 7. Propeller shaft 14 is disposed through the wall of chain housing 7 and journeled in suitable bearings therein. Propeller shaft 14 is in parallel spaced relation with double pinion gear shaft 10, shafts 10 and 15 forming a planar surface therebetween. Propeller shaft 14 is rotatably journeled about its horizontal axis while being stationary with respect to vertical axis of chain assembly housing 7. Sprockets 16 are disposed about and secured to propeller shaft 14 in aligned registration with sprockets 13 mounted upon shaft 10. Although the preferred embodiment of the present invention utilizes chain drive 15 to coupled sprockets 13 and 16, it is within the scope of the present invention to utilize a belt and pulley assembly in place of sprockets 13 and 16 and chain drive 15. Propeller 17 is mounted at the exposed end of propeller shaft 14 and upon the rotation thereof will provide the motive force to the vessel upon which the present invention is installed.

An understanding of the cooperative relationship between propulsion elements of the present invention can be best seen by reference to FIG. 2. FIG. 2 illustrates a top plan view of the propulsion elements of the present invention. As can be seen, power source drive shaft 1 is disposed through the outer wall of gear housing 2, power source drive shaft 1 being terminated at pinion or bevel gear 3. Pinion gear 3 is meshed with circular, outer rack gear 4 which is integral with the inner rack

gear 5. It can therefore be seen that rotation of outer rack gear 4 will result in the simultaneous rotation of inner rack gear 5. Inner rack gear 5 is meshed with pinion gears 11 and 12. Sprockets 13 are disposed about and secured to shaft 10, sprockets 13 being rotatable with shaft 10. Sprockets 13 are disposed within chain assembly housing 7, chain drive 15 being coupled to sprockets 13 within chain assembly housing 7. It can therefore be seen that the rotation of power source drive shaft 1 will transmit rotational movement to rack gear 4 and 5 about the vertical axis of chain assembly housing 7. The rotation of rack gears 4 and 5 will cause pinion gears 11 and 12 to rotate about their horizontal axis thereby rotating sprockets 13 and transmitting the torque to chain drive 15. Where the respective gear ratios are equal, the torque transmitted to chain drive 15 will be substantially equal to that present at power source drive shaft 1.

Referring again to FIG. 1, the manner in which the present invention combines the steering and propulsion functions can be best seen. As stated, chain assembly housing 7 is rotatably journeled in bearings 8 and 9, housing 7 being rotatably coupled with respect to the hull of the vessel. Steering gear 18 is concentrically disposed about and secured to chain assembly housing 7 within gear housing 2. Gear 18 is meshed with pinion gear 19, the rotation of gear 19 transmitting the steering rotational movement to steering gear 18 and chain assembly housing 7. Steering shaft 20 depends from steering pinion 19, steering shaft 20 being rotatably mounted through the wall of gear housing 2, steering shaft 20 being journeled in suitable bearings mounted upon gear housing 2. Concentrically disposed about and mounted upon shaft 20 is gear 21 adapted to mesh with external gear 22. The rotation of gear 21 is provided external to gear housing 2, the rotation of gear 21 being transmitted through steering shaft 20 and steering pinion 19. Since chain assembly housing 7 is fully rotatable upon bearings 8 and 9, rotation of steering pinion gear 19 will effect a full 360° rotation of the power output of propeller 17 thereby providing for full maneuverability without requiring reversing gears or other means for reversing the power source coupled to power source drive shaft 1. Although the preferred embodiment of the present invention is adapted for full 360° rotation, it is, of course, obvious that a reversible power source could be used for the rotation of power source drive shaft 1.

As stated, an object of the present invention is to isolate the chain drive assembly 15 and coupled sprockets 13 and 16 from the lubricating system for the remainder of the present invention marine propulsion and steering apparatus. Since propeller shaft 14 and the bearings journaling same will be submerged in water at all times during normal operation, it is possible that the seal at the journaling bearings could permit the passage of water into the interior of chain assembly housing 7. Since chain drive 15 and the respective sprocket drives 13 and 16 are sealed from the remainder of the gear members and the lubricating systems therefor, the entry of any water into the interior of chain assembly housing 7 will be totally isolated from the remainder of the system. There will be no substantial deleterious effect upon chain drive 15 and coupled sprockets 13 and 16 from water since the nature of the members and the isolation thereof will prevent any material damage. In this manner, the system cannot be contaminated by the

passage of the water within the system thereby providing for increased reliability.

Referring now to FIG. 3, the operation of the present invention marine propulsion and steering apparatus can be best seen. Chain assembly housing 7 is depicted by the dotted line illustrating the isolation of the chain drive assembly from the remainder of the propulsion and steering system. The rotation of power source drive shaft 1 imparts torque to pinion gear 3 which in turn translates the torque 90° imparting the rotation to outer rack gear 4. Outer rack gear 4 is integral with inner rack gear 5 again translating the imposed torque 90° at pinion gear 11. For the purpose of illustration, only pinion gear 11 is shown. Pinion gear 11 being fixedly attached to shaft 10, rotates shaft 10 and in turn, imposes rotational torque upon sprockets 13. Sprockets 13 provide the motive force to chain drive 15 and therefore to mating sprockets 16. The rotation of sprockets 16 imparts rotational force to propeller shaft 14. Since integral rack gears 4 and 5 are freely rotatable about chain assembly housing 7, the steering portion of the present invention allows the full utilization of the output of the power source irrespective of the direction in which propeller shaft 14 is disposed. As seen in FIG. 3, propeller shaft 14 has been moved to provide starboard movement of the vessel. Steering gear 18 is fixedly mounted about chain assembly housing 7, steering gear 18 being rotated through rotation of meshed steering pinion 19. From FIG. 3 can be seen that propeller shaft 14 can be rotated through a full 360° of arc and continue to transmit the full rotational power imposed upon power source drive shaft 1. In addition, a rotation force on power source drive shaft 1 could be reversed, the effect thereof merely reversing the directional arrows illustrated in FIG. 3.

The present invention, marine propulsion and steering apparatus, provides a highly simplified system for utilizing the power of an inboard motor and transmitting same in an efficient manner while simultaneously providing means for increasing the reliability of the system. The use of a chain drive assembly which is isolated from the remainder of the steering and propulsion system eliminates failure of the system due to water contamination. In addition, the ability to rotate the propulsion force through a full 360° of arc substantially simplifies the need for additional equipment to couple the power source to the present invention. The present invention marine propulsion and steering apparatus therefore provides a system for propelling and steering a marine vessel which is economical to fabricate and easier to maintain than the devices disclosed by the prior art.

I claim:

1. A propulsion and steering apparatus for use on a vessel comprising:
  - a. a rotational power source mounted upon the vessel in fixed relation thereto;
  - b. a housing rotatably mounted to said vessel for rotation about the vertical axis of said housing;
  - c. a propeller shaft rotatably mounted through said housing to rotate about its horizontal axis and being perpendicular to the vertical axis of said housing;
  - d. a gear shaft in parallel spaced relation to said propeller shaft rotatably mounted through said housing to rotate about its horizontal axis and being perpendicular to the vertical axis of said housing;

- e. means for transmitting torque between said propeller shaft and said gear shaft comprising first and second sprockets disposed about and secured to said propeller shaft and said gear shaft respectively and an endless drive member coupled about said first and second sprockets;
  - f. a first gear coupled to the power source;
  - g. a second gear coupled to and extending from said gear shaft;
  - h. coupling means for coupling gear surfaces rotatably disposed about said housing and coupled to said first and second gears; and
  - i. steering means for positioning said apparatus coupled to said housing.
2. A propulsion and steering apparatus as defined in claim 1 wherein said rotational power source is a unidirectional power source.
  3. A propulsion and steering apparatus as defined in claim 1 wherein said coupling means comprises a pair of concentric rack gears integral with one another.
  4. A marine propulsion and steering apparatus for use on a marine vessel comprising:
    - a. a rotational power source mounted upon the vessel in fixed relation thereto;
    - b. a housing member rotatably mounted to said vessel for rotation about the vertical axis of said housing;
    - c. a propeller member including a propeller shaft rotatably mounted through said housing to rotate about a horizontal axis and being perpendicular to the vertical axis of said housing member;
    - d. a pinion gear shaft member including a pinion gear shaft in parallel spaced relation to said propeller shaft and being rotatably mounted through said housing member to rotate about its horizontal axis and being perpendicular to the vertical axis of said housing member and a first pinion gear axially extending from an end of said pinion gear shaft;
    - e. an endless drive member coupled about said propeller shaft and said pinion gear shaft whereby the rotation of said pinion gear shaft is transmitted to said propeller shaft;
    - f. power means for coupling the rotational power of the power source including a second pinion gear coplanar with said pinion gear shaft member;
    - g. inner and outer integral, circular rack gears rotatably disposed about said housing member, said inner rack gear coupled to said first pinion gear and said outer rack gear coupled to said second pinion gear; and
    - h. steering means for rotating said housing member about its vertical axis for steering said apparatus.
  5. A marine propulsion and steering apparatus as defined in claim 4 wherein said rotational power source is a unidirectional power source.
  6. A marine propulsion and steering apparatus as defined in claim 4 wherein said steering means includes a circular gear disposed about and secured to said housing member and means for steering coupled to said circular gear whereby said housing member is rotatable through 360° of arc.
  7. A propulsion and steering apparatus for propelling and steering a marine vessel comprising:
    - a. a rotational power source secured to and in fixed relation to the marine vessel;
    - b. a chain assembly housing being rotatably mounted to the vessel for rotation about the vertical axis of said housing;

- c. a propulsion member including a propeller shaft rotatably mounted through said chain assembly housing and adapted to rotate about its horizontal axis, said propeller shaft being perpendicular to the vertical axis of said chain assembly housing and a propeller depending from an end of said propeller shaft;
- d. a gear shaft in parallel, spaced relation to said propeller shaft and being rotatably mounted through said chain assembly housing and adapted to rotate about its horizontal axis and being perpendicular to the vertical axis of said chain assembly housing, said gear shaft having a first beveled gear depending from an axial end thereof;
- e. first and second sprockets disposed about and secured to said gear shaft and said propeller shaft respectively, and being within said chain assembly housing;
- f. a chain drive member coupled between said first

15

20

25

30

- and second sprockets;
- g. power means for coupling the rotational power of the power source including a second beveled gear coplanar with said gear shaft and first beveled gear;
- h. a circular rack gear member having inner and outer concentric rack gears rotatably disposed about said chain assembly housing, said inner rack gear coupled to said first beveled gear and said outer rack gear coupled to said second beveled gear; and
- i. steering means for rotating said chain assembly housing through 360° of arc including a circular gear disposed about and secured to said chain assembly housing.

8. A propulsion and steering apparatus as defined in claim 7 wherein said rotational power source is a unidirectional power source.
